UNITED STATES PATENT OFFICE.

ALLEN E. OSTRANDER, OF PATERSON, NEW JERSEY, ASSIGNOR TO AMERICAN CAR & FOUNDRY COMPANY, OF ST. LOUIS, MISSOURI, A CORPORATION OF NEW JERSEY.

CAR CONSTRUCTION.

No. 847,503.

Specification of Letters Patent.

Patented March 19, 1907.

Application filed June 14, 1906. Serial No. 321,774.

To all whom it may concern:

Be it known that I, ALLEN E. OSTRANDER, a citizen of the United States, residing at Paterson, Passaic county, New Jersey, have 5 invented a certain new and useful Improvement in Car Construction, of which the following is a full, clear, and exact description, such as will enable others skilled in the art to which it appertains to make and use the 10 same, reference being had to the accompanying drawings, forming part of this specification, in which the figure is a transverse sectional view through a car-wall constructed in accordance with my invention.

15 This invention relates to the construction of cars, and particularly to the construction of the belt-rail of a passenger-car.

The object of my invention is to provide a 20 strong and rigid construction and still permit the use of a comparatively light-weight angle for the belt-rail.

In constructing steel passenger-cars of 25 great length in which the sides of the car carry the load it has heretofore been necessary to use a bulb-angle of a thick or heavy section or having a very wide horizontal leg in order to insure the required strength. The use of a bulb-angle having a wide horizontal leg is objectionable, as the horizontal leg 30 projects too far beyond the side wall of the car, while the use of an angle having thick legs is objectionable, in that it requires a great deal of time and labor to drill holes therein to receive the rivets or fastening devices which attach the angle to the side wall 35 of the car.

My improved construction overcomes both 40 of the objectionable features above referred to and permits the use of a comparatively light-weight angle, or, if desired, an angle on the outside of the car-wall can be entirely dispensed with, this being accomplished by recessing the vertical posts which carry the side wall and arranging a longitudinally-ex- 45

tending strengthening member in these recesses inside of the plates which form the side wall of the car. I have herein shown the vertical posts as being bent inwardly to form a recess to receive the strengthening mem- 50 ber; but, if desired, the posts may be pro- vided with notches to receive said strength- ening member, and wherever I have used the

term "recess" in the claims I mean a space which is formed either by bending or notching the posts.

55

Referring to the drawing, which represents the preferred form of my invention, 1 and 2 designate, respectively, the lower and upper sills of a car, and 3 designates one of the vertical posts which extend from the lower to 60 the upper sill and carry the plates 5, which form the side wall of the car, said posts being offset inwardly at their lower ends to receive the lower sills. As herein shown, the post 3 consists of an angle; but it will of course be 65 understood that any form of post could be used without departing from the spirit of my invention.

As shown in the drawing, the post 3 is offset inwardly at 4 to form a recess, the other 70 posts being constructed in the same manner, and arranged in these recesses inside of the side-wall plate 5 is a strengthening member consisting of a bar 6, that extends longitudinally of the car and is connected to the posts 75 and to the side-wall sheathing-plate 5 by suitable fastening devices 7. A bar 6 of any thickness can be used as the strengthening member, as it is immaterial how far inwardly the posts are offset, so that it is thus 80 possible to produce a plate-girder car-wall possessing the required strength without increasing the width of the car, as has heretofore resulted when a bulb-angle having a wide horizontal leg was used, the sill 1 forming 85 the lower chord of the plate-girder and the bar 6 forming the upper chord. Preferably a bulb-angle 8 is arranged along the outside of the upper edge of the plate-girder and is connected to the strengthening mem- 90 ber preferably by the same fastening devices which secure said member to the vertical posts and sheathing-plate 5. If desired, however, the member 8 could be in the form of a rolled-steel angle instead of a bulb-angle, 95 as herein shown.

While I have herein shown my improved construction as being embodied in a passenger-car, it will of course be understood that other types of cars can be constructed in the same manner without departing from the spirit of my invention. Furthermore, it will be obvious that this same construction of belt-rail could be embodied in a car in which

short side posts were used—namely, posts that extended only between the lower sill and belt-rail.

The plates 9, which form the outside sheathing of the upper half of the car-wall, are fastened to the vertical posts 3 and at their lower edges are bent laterally, so as to lie upon the upper face of the horizontal leg of the bulb-angle 8, and may be connected thereto by rivets or bolts 10, thereby producing a very neat construction which covers the upper edge of the plate-girder that forms the lower half of the car-wall, so that the break in the wall of the car is completely hidden.

15 While I have herein shown the posts 3 as being continuous from the lower to the upper sills of the car, it should be understood that these posts could be formed in two sections spliced at the belt-rail.

20 Having thus described my invention, what I claim as new, and desire to secure by Letters Patent, is—

1. In a car construction, a plate-girder wall consisting of longitudinally-extending upper and lower chords, a plate connected to said chords, posts arranged on the inside of said plate and recessed to receive said upper chord, and a bulb-angle extending longitudinally along the outside upper edge of the 30 plate-girder; substantially as described.

2. In a car construction, a plate-girder wall consisting of longitudinally-extending upper and lower chords, a plate connected to said chords, posts arranged on the inside of said plate and recessed to receive said upper chord, and a bulb-angle extending longitudinally along the outside upper edge of the 35 plate-girder and connected to said upper chord; substantially as described.

40 3. In a car construction, a plate-girder wall consisting of longitudinally-extending upper and lower chords, a plate connected to said chords, posts arranged on the inside of said plate and recessed to receive said upper chord, a bulb-angle arranged along the outside upper edge of said plate, and fastening devices passing through the vertical leg of said angle, the plate, the upper chord and the post; substantially as described.

45 4. In a passenger-car construction, vertically-arranged posts provided at approximately the centers thereof with offsets which extend inwardly to form recesses, a longitudinally-extending strengthening-bar arranged in these recesses and lying flush with the outer faces of the posts, and a side-wall plate connected to said strengthening-bar; substantially as described.

50 5. In a passenger-car construction, vertically-arranged posts provided at approximately the centers thereof with offsets which extend inwardly to form recesses, a longitudinally-extending strengthening-bar arranged in these recesses and lying flush with

the outer faces of the posts, a side-wall plate 65 connected to said strengthening-bar, and a longitudinally-extending angle arranged on the outer face of said plate and connected to said bar; substantially as described.

6. In a passenger-car construction, vertically-arranged posts provided with recesses, a longitudinally-extending strengthening-bar arranged in these recesses and lying flush with the outer faces of the posts, a side-wall plate connected to said strengthening-bar, a 70 longitudinally-extending angle arranged on the outer face of said plate and connected to said bar, and a plate forming the upper portion of the car-wall and having its lower edge bent laterally to engage the horizontal leg of 75 said angle; substantially as described.

7. In a passenger-car construction, a lower sill, vertically-extending angles connected to said sill to form the posts of the side wall of the car and provided with recesses intermediate their ends, side plates engaging the outer faces of said posts and connected to the lower sill, a longitudinally-extending strengthening-bar arranged in the recesses of the posts on the inside of the side 90 plates, and a longitudinally-extending bulb-angle arranged on the outside of said side plates and connected to said strengthening-bar; substantially as described.

8. A car comprising a side wall, metal 95 posts on the inside of said side wall and constructed to receive an approximately straight longitudinally-extending flat metal bar which is arranged between the side wall and said posts at the belt-rail of the car; substantially 100 as described.

9. A car comprising a side wall, a longitudinally-extending strengthening member arranged on the inside of said wall, metallic posts on the inside of the side wall constructed to receive said strengthening member, and an angle extending parallel to said strengthening member and forming the belt-rail of the car; substantially as described.

10. A car comprising metallic posts constructed to receive an approximately straight strengthening member which extends longitudinally of the car, a side-wall plate connected to the outer faces of said posts and engaging said strengthening member, and a 110 longitudinally-extending angle forming the belt-rail of the car and being connected to said strengthening member; substantially as described.

11. In a side-wall framing for a car, a plurality of vertical metal posts recessed at approximately their centers, and a straight metallic strengthening member extending transversely of said posts and arranged in the recesses thereof; substantially as described.

12. A side-wall framing for a car consisting of upper and lower sills, a plurality of vertical metallic posts offset inwardly at their

upper and lower ends to receive said sills, and a strengthening member extending parallel to said sills and being connected to said vertical posts, said posts being recessed intermediate the upper and lower sills to receive said strengthening member; substantially as described.

In testimony whereof I hereunto affix my signature, in the presence of two witnesses, this 5th day of June, 1906.

ALLEN E. OSTRANDER.
